BOBBIN LIFTING MECHANISM

John Hamilton Larmuth, Hill Crest, Upper
Colwyn Bay, North WalesApplication December 2, 1938, Serial No. 243,557
In Great Britain December 18, 1937

5 Claims. (Cl. 242—130)

This invention relates to bobbin lifting mechanisms for stranding, twisting, lapping and the like machines wherein bobbins which carry the material are placed in cradles mounted in a rotary member such as a tube having apertures or a metal framework.

The main object of my invention is to dispense with the need for overhead hoisting tackle for lifting the bobbins on to the cradles, whilst at the same time avoiding the provision of hoisting tackle on the cradles themselves for hoisting the bobbins from a runway situated beneath the rotary member, and without requiring a special design of bobbin for use with the mechanism.

According to the invention bobbin lifting mechanism for stranding and other machines comprises for each cradle, a platform separate from but adapted to fill a gap in an interrupted runway beneath the rotary member, the said platform being adapted to be raised and thereby raise a bobbin standing thereon into the cradle to a position where it can be mounted thereon.

The platform may be connected to lifting arms operated by a hand wheel or the equivalent operationally connected by suitable means to the said arms, there being a hand wheel or the equivalent for operation of each platform or for alternative operation of each two adjacent platforms.

A radius link may be connected to the platform to cause it to tilt when raised and thereby prevent rolling of the bobbin thereoff in one direction.

Automatic or hand controlled stop means may be provided in connection with the platform to prevent rolling of the bobbin thereoff in the reverse direction.

The platform is supported by the said arms by means which hold it a distance above the same when in raised position whereby the platform can pass up through the apertured rotary member and between the sides of the cradle into the requisite position without the said arms or other parts fouling the rotary member or cradle.

The said platform is preferably rotatably mounted on a cross rod by means of lugs or brackets which maintain the platform a distance above the said cross rod, radius links connected to the platform and to a stationary part operating to control and vary the angular position of the platform during lifting.

The said arms and link are preferably connected to a stationary part of the machine by means of brackets mounted on the stationary part, the points of connection of the arms and link to the brackets being at a lower elevation than the cradles.

For operation of the arms they are preferably connected to the two ends of two chains which run on sprocket wheels adapted to be rotated by means of the said hand wheel or the equivalent, the said chains also running over carrier wheels.

Alternatively the said chains or a different kind of hoisting member may be adapted to be wound on to and off drums operated by the said hand wheel or the equivalent.

In the accompanying drawings, which illustrate a constructional example of the invention—

Figure 1 is a fragmentary side view in section of a bobbin lifting mechanism on a stranding and the like machine.

Figure 2 is an end view in section thereof.

Figure 3 is a fragmentary side view showing a bobbin lifting mechanism of another construction.

Figure 4 is a fragmentary side view of a bobbin lifting mechanism and illustrates a third construction.

Figure 5 is an end view in section thereof.

Figure 6 is a detached side view illustrating a detail of a fourth construction, and

Figure 7 is a plan view thereof.

Referring to the drawings, in the construction shown in Figures 1 and 2, as applied by way of example to a stranding and the like machine having a tubular member 1 provided with apertures 2 in its periphery and mounted in bearings 3 provided on the side members 4 of a stationary frame and carrying inside it cradles such as 5 by a trunnion mounting whereby the cradles 5 are free to remain stationary whilst the member 1 rotates, I provide at substantially the elevation of the longitudinal centre of the member 1, a rail 6 extending between adjacent frame bearings 3 outside the member 1, at each side of the machine. A depending bracket 7 is secured to each rail 6. To the lower end of each bracket 7 is pivoted at 8 an arm 9 and the two arms 9 are connected together by a cross rod 10 situated a suitable distance from the end of each arm 9 and connecting the arms 9 together. The end of the arm 9 is connected at 11 to one end of a driving chain 12.

The rod 10 has two lugs 13 fixed to it and the lugs 13 projecting downwardly to a suitable distance from the sides of a platform comprising two rail portions 14 for the flanges 15 of the bobbin 16 to roll and rest on and two side flanges 17 to guide and hold flanges 15 of the bobbin 16 laterally. The rod has fixed to it an arm 18 which is connected by a pivotal, telescopically adjustable link 19 to one of the depending brackets 7 at a point 20 above the ful-

50
55
55

crum 8 of the respective arm 9. The relative positions of the pivotal point 20 on the one hand and the pivot 8 of the arm 9 on the other hand are such that when the platform comprising the parts 14 and 17 is in its lowest position, the rail portions 14 are horizontal, but that when the arm 9 and therefore the said platform are raised, the said platform tilts out of the horizontal, whereby rolling of the bobbin 16 off the said platform is prevented in one direction.

The flanges 17 are provided with lugs 21 having slots 22 or holes for the insertion of a stop pin 23 across one end of the platform.

The chains 12 pass over the upper side of sprocket carrier wheel 24 and the under side of sprocket wheels 25 mounted in brackets 26 secured to the said rail 6. The sprocket wheels 25 are provided on a shaft 27 which extends across the machine beneath the member 1 and is also supported in the brackets 26. The shaft 27 is provided with a hand wheel 28 at one side of the machine. The shaft 27 has also a toothed locking wheel 29 which by cooperation with a double-toothed pawl 30 pivoted at 31 and fitted with a handle 32 enables the shaft 27 to be locked against rotation in one or the other direction at will according to the position into which the handle 32 is moved. When the handle 32 is held in the mid-position, the pawl does not engage the wheel 29 and the shaft is therefore free to rotate in both directions.

In operation, the bobbin 16 is rolled onto the platform beneath the member 1 and the stop pin 23 or other device is brought into position 35 to prevent it rolling back.

The hand wheel 28 is then rotated in the requisite direction and by driving the two chains 12 raises the two arms 9 uniformly and thus causes the platform to rise. As soon as the platform commences to rise, the link 19 causes it to tilt in such a direction as to prevent by gravity the bobbin 16 from rolling forwards off the platform. The arms 9 continue to rise under the pull of the chains 12 and cause the bobbin 16 and platform carrying the same to enter member 1 from below through one of the apertures 2 therein and the bobbin 16 to then rise upwards between the sides of the cradle 5 until the central hole 33 provided in the bobbin 16 for the usual mandrel is situated above the tops of the said sides. The parts are then in the position shown in dot-and-dash lines. The usual mandrel is then inserted through another of the apertures 2 into the said hole 33 above the tops of the sides of the cradle 5, whereupon the chains 12 are slackened off by means of the hand wheel 28 so as to allow the arms 9 and therefore the platform and bobbin 16 to sink until the said mandrel has sunk into and is supported in the slots 34 provided for it in the cradle 5, whereupon the bobbin 16 remains suspended in the correct position in the cradle 5 and further slackening of the chains 12 allows the arms 9 and platform to sink into the initial positions shown in full lines, with the platform again horizontal and ready to receive another bobbin.

In a stranding and the like machine there are a plurality of cradles 5. I provide a platform, cross rod, arms, link and arm and link supporting brackets for each cradle and there may be a separate chain and system of sprocket, shaft and hand wheel for each cradle. I however prefer to arrange the said arms and so forth of each pair of cradles in such a manner that one hand wheel serves to operate the lifting mech-

anisms of two adjacent cradles. An arrangement of this kind is shown in Figure 3. In the said figure the arms 9 face each other and move in anti-clockwise and clockwise direction respectively when rising, the pair of arms 9 corresponding with one of the two cradles 5 being connected to one end of the pair of chains 12 and the pair of arms 9 belonging to the other cradle 5 to the other ends of the same pair of chains 12. The chains 12 are of sufficient length to enable both of the platforms to simultaneously occupy their lowermost position, as shown. By this means one hand wheel 28 serves to operate both lifting mechanisms separately and therefore to lift bobbins separately into either of the two cradles 5.

It is to be noted that the mounting of the platforms on the cross rods 10 by means of lugs 13 or the equivalent which cause the platforms to be situated at a substantially higher elevation than the cross rods 10 enables the bobbin to be raised to the requisite extent without any parts of the mechanism fouling or being obstructed by the member 1 or cradle 5.

To facilitate the placing of the bobbins on the platforms I provide a track situated beneath and parallel with the member 1 and composed of stationary sections 43, each having rail portions for the bobbin rims to roll on and side flanges for guiding the bobbin laterally similar to the portions 14 and flanges 17 of the platforms, the sections 43 being so arranged that when the two platforms of a pair of lifting mechanisms are in their lowermost positions there is one of the said sections 43 bridging the gap between them 35 and forming a continuation thereof, the said sections also supporting one end of each platform when in the lowermost position, by forming the said end to overlap the section without obstructing the rolling of the bobbin on to and off the platform. This enables a bobbin to be rolled over one platform and the said section to the next platform. Thus when all the platforms are in the lowermost position, a bobbin can be inserted on the track at one end of the machine and rolled along the sections and platforms into position beneath any one of the cradles for being lifted thereinto by the respective platform.

The use of the pawl 30, when set in the requisite position by the handle 32, prevents accidental falling of the platform during the lifting operation and whilst the usual mandrel is being inserted in the hole 33 of the bobbin.

If preferred the link 19 may be arranged to maintain the platform in a horizontal state throughout the whole of its movement, it then being necessary to provide stop means such as 21, 22, 23 or the like at both ends of the platform in such a way as to prevent the bobbin 16 rolling thereof in either direction.

In lieu of the said arms, links, chains and so forth, four lifting chains or cables 35, Figures 4 and 5 or 6 and 7 or their equivalents may be connected to arms 36, Figures 4 and 5 on the cross rod or to depending, cranked parts 37, Figures 6 and 7 on the platform in lieu of the said cross rod to raise and lower the platform whilst maintaining it in a constant angular position, means being provided for winding 70 the four chains up and down equally by the aid of a single hand wheel or the like. For example there may be two shafts 38, Figures 4 and 5, each provided with two drums 39, there thus being one drum 39 for the winding on of 75

each cable 35, one of the shafts 38 being provided with a hand wheel 40 and the two shafts 38 being connected to rotate together by means of an endless driving chain 41 engaging a sprocket wheel 42 on each of the shafts 38.

5. I claim:

1. A bobbin lifting mechanism for stranding and other machines wherein bobbins which carry the material are placed in cradles mounted in a 10 rotary member having apertures through which the bobbins are placed in and removed from the cradles, comprising in combination spaced stationary bobbin track sections extending longitudinally along the machine vertically beneath 15 the rotary member, liftable bobbin track sections situated between the stationary track sections and forming with the stationary sections a continuous track from end to end of the machine for rolling the bobbins along longitudinally beneath 20 the machine into position beneath the rotary member, and means for lifting the liftable bobbin tracks separately at will for pushing the bobbins thereon through the apertures in the rotary member and into position in the cradles.

25. 2. A bobbin lifting mechanism for stranding and other machines wherein flanged bobbins which carry the material are placeable in cradles mounted in a rotary member having apertures through which the bobbins are placed in and 30 removed from the cradles when the rotary member is stopped, comprising in combination, a plurality of spaced pairs of stationary rails arranged in alignment longitudinally beneath the rotary member for the flanges of the bobbins to roll 35 along, a plurality of pairs of raisable rails disposed between the pairs of stationary rails for the flanges of the bobbins to roll over from one pair of stationary rails to the next pair of stationary rails, downward projections on each pair 40 of raisable rails, flexible draft members connected to the downward projections and rotary means on the machine for hoisting up the said draft members and thereby raising the pair of raisable rails and therefore pushing the bobbin thereon up through one of the apertures in the 45 rotary member into the cradle.

3. A bobbin lifting mechanism for stranding and other machines wherein flanged bobbins are employed in cradles mounted in a rotary member having apertures through which the bobbins are inserted and removed from the cradle from beneath the said cradle, comprising a multiple part bobbin track on which the bobbins are rolled longitudinally beneath the machine into

position beneath the cradles, some parts of the said track being fixed and other parts thereof being liftable, downward projections on the movable parts of the tracks, in combination with swing arms pivoted to a stationary part and 5 connected to the downward projections for raising the liftable parts from below, chains connected to the ends of the swing arms of two of the liftable portions of the track, a shaft mounted on the machine, toothed wheels mounted on 10 the shaft and engaged by the said chains, and a hand wheel on the shaft for rotating it and the said toothed wheels actuating the said chains and thereby raising either of the said liftable portions at will. 15

4. A bobbin lifting mechanism for stranding and other machines wherein flanged bobbins are employed in cradles mounted in a rotary member having apertures through which the bobbins are pushed from below into the said cradles, 20 comprising a longitudinal track beneath the rotary member for the flanges of the bobbins to roll on, raisable sections of the said track for supporting and raising the bobbins through the said apertures into the cradles, downward projections on each movable section, a horizontal spindle secured to the projections, swing arms loosely connected to the spindle, radius arms secured to the said spindle, stationary pivots on which the swing arms swing, stationary pivots 30 above the last named pivots, a pivotal link connecting the second named pivots to the radius arms, and hand-operable means acting on the swing arms for raising the same. 25

5. In a bobbin lifting mechanism for stranding 35 and other machines wherein flanged bobbins are employed in cradles mounted in a horizontal rotary member having apertures through which the bobbins are inserted in and removed from the cradle, a sectional bobbin runway arranged 40 longitudinally of the rotary member for rolling the bobbins along on its flanges into position beneath the cradles and comprising fixed sections and raisable sections interposed between the fixed sections and remaining permanently in 45 register with the cradles in combination with means connected to the raisable sections for preventing the bobbins from rolling on their flanges thereoff when the raisable sections are raised, and means for raising the said sections 50 and therefore pushing the bobbins thereon up into the said cradles.

JOHN HAMILTON LARMUTH.
